UNITED STATES PATENT OFFICE.

ALBERT O. BUCKIUS, JR., OF CHICAGO, ILLINOIS, ASSIGNOR TO THE NATIONAL MALLEABLE CASTINGS COMPANY, OF CLEVELAND, OHIO.

JOURNAL-BOX.

1,145,347.

Specification of Letters Patent.

Patented July 6, 1915.

Application filed December 23, 1913. Serial No. 808,314.

To all whom it may concern:

Be it known that I, ALBERT O. BUCKIUS, Jr., a citizen of the United States, residing at Chicago, Cook county, Illinois, have invented new and useful Improvements in Journal-Boxes, of which the following is a specification, reference being had to the accompanying drawings, in which—

Figure 1 is a section of a journal box embodying my invention and showing the lid in close position; Fig. 2 is a section showing the lid in opened position; Fig. 3 is a section of the box showing the lid-operating mechanism in elevation, and Fig. 4 is an elevation of mechanism for securing the lid to the box.

My invention relates to journal boxes and provides a box having a lid held tightly closed against all movements, except a pivotal one, by a spring lever regardless of the wear and tear to which the lid and meeting faces of the box may be subjected.

My invention also consists in the improved construction which I shall hereinafter describe and claim.

Referring to the drawings, 2 indicates the journal box and 3 the journal box lid. The box 2 has bosses 4 concentric with the axis of the hinge pin 5, which seats in the pin apertures of the hinge lug 6. The lid 3 is attached to the box 2 by circular socket bearings 7, which bear on the bosses 4, and by the hinge pin 5. The lever and spring mechanism is comprised of a spring 8 of substantially U-shape, in each arm of which are formed coils of loops 9, which provide registering apertures 10 for the insertion of a pin 11 upon which the spring 8 has its pivot. The upper or closed end 12 of the spring 8 is bent at an angle to the body of the spring, and mounted thereon is a wearing shoe 13. The shoe 13, which is preferably attached to the part 12 by bendable lugs 14, provides a cam surface adapted to engage and slide upon the cam surfaces 15 and 16 of the hinge lug 6.

The ends 17 of the spring 8 are secured in small pockets 18 formed in the lid 3 near its inside lower edge, and the spring is pivoted intermediate of its length by the pin 11, the ends of which seat in sockets 19 on the inner face of the lid. The sockets 19 are open at their upper sides, as is shown in dotted lines in Fig. 3, to permit insertion of the pin 11.

When the spring 8 is in position and secured to the lid by the sockets 19 and the pin 11, and the lid is applied to the box, the contact of the shoe 13 with the surface 15 or the surface 16 causes a tension on the spring and prevents the pin 11 from coming out of its sockets 19.

When the lid 3 is in closed position, as is shown in Fig. 1, the shoe 13 is held against the cam surface 15 by the action of the spring 8, which is under tension, and a pressure is exerted between the pivot 11 and the hinge lug 6, which holds the bosses 4 of the latter securely against the socket bearings 7. This coöperation of the parts prevents any sliding movement of the lid 3 in a vertical direction and compensates for wear when the initial fit of the parts has been lost through service. As the reaction of the spring lever 8 against the lid tends to hold the lid against, rather than away from, the box by reason of its bearing against the cam surface 15, the lid will nevertheless remain tight against the box even though the hinge pin 5 be removed or broken.

In opening the lid 3 from its closed position the shoe 13 moves across the cam surface 15, thereby increasing the compression of the spring until the lid has been moved so that the rear end of the shoe 13 has passed the meeting point 20 of the cam surfaces 15 and 16, from which point it will slide along the cam surface 16 and will allow the spring 8 to reexpand. The spring 8 is under compression at all times, but it is under the greatest compression when the rear end of the shoe 13 is passing the meeting point 20 of the cam surfaces 15 and 16, from which point the spring 8, in reexpanding, throws the lid positively either to open or to closed position.

It is obvious that various changes may be made in the construction which I have shown and described herein without departing from my invention.

What I claim is:

1. In a journal box, a hinge lug having cam surfaces thereon, a lid secured to the hinge lug, a spring lever mounted on the lid, having coiled portions comprising pivotal points of attachment to the lid, a retaining pin for the coiled portions, and an angled portion comprising means coöperating with the cam surfaces on the hinge lug

for increasing the compression of the spring during a portion of the opening or closing movement.

2. In a journal box, a hinge lug having convergent faces, a lid secured to the hinge lug, a spring having a pivotal mounting near its middle portion on the lid, and a wearing shoe secured to the spring and being adapted to co-act alternately with the convergent faces of the hinge lug, and the spring being adapted of itself to press the said wearing shoe inwardly upon one of said faces and thereby hold the lid tightly shut.
3. In a journal box, a hinge lug having cam surfaces thereon, a lid having a pivotal mounting on said lug, and a flexible lever pivotally mounted upon said lid, one end of said flexible lever reacting outwardly against said lid, the other end of said lever reacting outwardly against a cam surface on the hinge lug, and an intermediate portion of said flexible lever reacting inwardly against its point of pivotal attachment to the lid, whereby said lid, when in closed position, is pressed inwardly against the

mouth of the box at its top and bottom edges.

4. In a journal box, a hinge lug, a lid pivotally mounted thereon, and a flexible lever pivoted to the lid near the middle of 30 said lid, said flexible lever, when the lid is closed, reacting outwardly at one of its ends against the hinge lug and reacting inwardly at an intermediate portion on its point of pivotal attachment to the lid. 35

5. In a journal box, a hinge lug having cam surfaces thereon, a lid pivotally mounted on said box, and a spring pivotally mounted upon said lid, one end of said spring, when the lid is closed, being in engagement with and being pressed inwardly by a cam surface, such pressure being transmitted through the spring to the pivotal mounting, to hold said lid tightly against the mouth of the box. 40
